UNITED STATES PATENT OFFICE.

DAVID MAXWELL, OF OAKMONT, PENNSYLVANIA.

APPARATUS FOR TUNNELING.

No. 867,284.

Specification of Letters Patent.

Patented Oct. 1, 1907.

Application filed November 24, 1905, Serial No. 288,879. Renewed July 13, 1907. Serial No. 383,625.

To all whom it may concern:

Be it known that I, DAVID MAXWELL, of Oakmont, Allegheny county, Pennsylvania, have invented a new and useful Apparatus for Tunneling, of which 5 the following is a full, clear, and exact description, reference being had to the accompanying drawings, forming part of this specification, in which:

Figure 1 is a vertical longitudinal section of a tunneling machine embodying my invention; Fig. 2 is a 10 sectional plan view on the line II-II of Fig. 1; Fig. 3 is a rear elevation of the machine; Fig. 4 is a front elevation; Fig. 5 is a vertical cross-section of the tunnel looking toward the face; and Fig. 6 is a diagram view illustrating the method of blasting.

15 The initial operation in the method of tunneling which I employ is illustrated in Fig. 5. By means of my machine which I will describe hereinafter I form in the rock of the tunnel a channel cut 2 of arch form and of suitable depth, preferably about four feet, 20 the depth being governed by the length of the channeling tool which it is convenient to employ. I also drill in the face of the rock, preferably at the same time with the forming of the channel-cut a series of blast-holes 3 which slant upward, their precise direction being determined by the nature of the rock, as 25 will be understood by those skilled in the art. I also drill at the same time in the face of the rock a series of blast-holes 4 above the channel-cut for the purpose of blasting out an exterior space for the accommodation 30 of the timbering and masonry where the rock is soft and the tunnel therefore requires to be lined.

After the channel 2 has been cut and the holes 3 and 4 drilled as above stated, the drilling and channeling machine is withdrawn from the face of the 35 rock, and the work of blasting is begun. The first blast is made with the top row of the holes 3, and with the holes at the center of the series 4. These blast-holes 3 are directly under the top of the channel-cut and the holes 4 in which the first blasting is done are 40 directly above the same, so that the effect of the first blast is to make a clearance space beneath the apex of the channel-cut 2 and directly above the same and to discharge the loosened rock in great part forwardly, causing it to fall upon aprons at the base of the tunnel 45 as explained below. Some of the loosened rock will, however, remain at the top of the face in which are the holes 3. The next blasting is done in the row of holes 3 next below, and also in the holes 4 at the side of the space above the channel-cut which has been formed by 50 the preceding blast. This discharges an additional mass of rock from below the channel-cut upon the apron at the base of the tunnel together with the loose rock remaining from the preceding blast, and also widens the blasted space above the channel. The work of blasting 55 is thus continued, each successive blast being

made in a row of holes 3 below the last preceding one, and in holes 4 successively outward from the middle.

The distance between the last two rows of holes, 4^a and 4^b, is preferably small so that only a relatively small amount of work will have to be done in blasting 60 these holes, and a light charge of explosive being used the rock will not be shattered and a solid seat 4^b will be formed for the timbering and masonry to spring from. When the blasting is finally completed it affords a blasted space of the shape indicated in diagram in 65 Fig. 6, the upper portion being of greater width than the lower portion and having seats 4^b for the masonry and timbering as above stated.

If desired the seats 4^b can be formed by channeling. At each successive blast the material dislodged thereby 70 falls upon a carrier which extends from side to side of the tunnel, and when the entire face of the rock has thus been blasted, it is transferred from the carrier to cars in the tunnel, and the carrier being withdrawn, the drilling and channeling machine is again advanced, 75 and the work of channeling and drilling followed by blasting is repeated.

As the tunneling proceeds the timbering is set in the widened space at the top of the tunnel and can be continued so as to follow the operation of tunneling very 80 closely, say within about twelve feet of the end of the face of the rock. The channeling and drilling machine is provided with a surrounding shell forming a roofed structure on which the workmen may stand in placing the timbers and on which the upper drills and upper 85 channeling carriage are supported.

The wider space at the top of the tunnel which is formed by the blast-holes 4 is of great advantage because it enables the timbering to be carried on concurrently with the drilling and enables the drilling and 90 channeling machine to be advanced and drawn back without interference by the timbering, which being in a space around the outline of the tunnel proper leaves a full opening for the passage of the machine. The masonry is applied preferably when the tunnel bore is 95 finished. The rails upon which the drilling machine and the loading cars travel are added in sections preferably four feet at a time, after each complete operation of blasting the face of the rock.

Figs. 1, 2, 3 and 4 show the channeling and drilling 100 machine. The shell or frame of this machine consists of a plate structure 5 strengthened on the inside by stiffeners 6 and composed preferably of plates having attached marginal angles which are placed preferably at the joints of the plates; and if desired the outside 105 of the shell may be similarly strengthened on the circular upper portion by stiffeners 7. This frame must support the drilling and channeling machinery and must also be hollow so as to permit the apron and loading cars to pass through it, so that it will not be necessary 110

sary after each blast to move the machine entirely from the tunnel, which if the tunnel were long would be a slow and expensive operation.

The frame is mounted upon wheels 8 which run upon

- 5 a track 9, and for the purpose of propelling the machine on the track to move it into channeling and drilling position or to retract it from the face of the rock, I prefer to employ a motor 10 connected by gearing 11, clutches 12, worm-gear 13 and shaft 14 with a pinion 15 which is in gear with a rack 16 applied to the side of the rail. This rack may also form a splice-bar connection between the rails, and when the shafts 14 are driven the pinions cause the machine to travel forward or back along the rails as may be desired. The same motor 10
- 15 may also be connected through the gearing 11, clutches 16, worm-gearing 17 and gearing 18 with screw-shafts 19 passing through nuts in a vertical head or frame 20 which has a forwardly projecting portion 22 carrying the drills 21 and hinged to the frame 20 by a horizontal
- 20 pivot 23 and adapted to be swung vertically on said pivot by a cylinder 24 operated preferably by water, so that the angle of inclination of the projecting portion 22 may be varied; and in conjunction with the vertical motion of the frame 20 provided for by the screw-shafts
- 25 19 a wide range of direction and position may be given to the drills 21. I show four of the drills 21. A still wider range of direction is afforded to them by mounting them on a tilting head 25 which is pivoted on an axis 26 to the portion 22 of the frame and is provided
- 30 with worm-wheels 27 adapted to be rotated by simultaneously actuating the worms 28 so that the head 25 may be turned on its pivot at any desired angle, or may be turned nearly an entire revolution, so as to direct the drills 21 downwardly for the purpose of drilling
- 35 vertical holes in the floor of the tunnel if desired.

Each outer drill cylinder 29 together with an adjacent drill cylinder 30 are mounted on laterally sliding frames or carriers 31 on the head 25, each cylinder being mounted on a vertical trunnion 32 on which it can be

- 40 swung laterally. Each frame 31 is movable in a horizontal direction by a traveling nut 33 set on a screw-shaft 34 adapted to be turned by a hand-wheel 35 or other suitable device.

The actuating cylinders of the drills 21 may be raised

- 45 by the screw-shafts 19 and also varied in direction by the mechanism above described, so as to drill holes in any portion of the face of the tunnel below the channel cut, and at any desired inclination.

The holes which are drilled outside of the channel

- 50 cut are made by drills mounted on the outside of the frame 5 of the machine. These drills 36 of which there may be any desired number are operated by percussion-cylinders 37 connected by vertical trunnions and clamps 38 to columns 39 along which they

- 55 may be adjusted and clamped in position. The columns 39 are carried by carriages 40 mounted on a pair of the stiffeners 7 which form rails therefor and have attached thereto racks 41 in which mesh pinions

- 42 on the carriage operated by worm-gearing 43 so

- 60 that the carriage may be moved around the exterior of the frame to bring the drills to any desired position thereon. The columns 39 are strengthened by braces 44. The adjustment of the cylinders 37 on

- 65 their trunnions and their lateral adjustment on the

columns of the frame give each of the drills 36 a wide range of adjustment of position and direction.

For the purpose of holding the projecting portion 22 of the frame 20 at the angle to which it is adjusted on its pivot, I employ locking devices 45 (Figs. 1 and 70 2) which are hinged at 46, and are connected by lever-arms 47 and a shaft 48 to an operating lever 49, by which they may be retracted. They are preferably forced forwardly by springs 50 which hold them in engagement with radially arranged ribs 51 on the 75 sides of the portion 22 of the frame, thus holding the frame securely in any position to which it is adjusted by operation of the cylinders 24.

The apparatus by which the channel-cut 2 is formed in the rock is best illustrated in Figs. 1-4. The 80 apparatus comprises vertically-sliding frames 52, mounted on the inside of the frame 5 of the machine, and carried by nuts 54 on vertical screw-shafts 55, driven through gearing 56 from a motor 57, so that the sliding head 52 can be raised and lowered to any 85 position desired. The mechanism is arranged so that these heads can be moved up and down substantially without interruption in the manner of a channeling machine so that the tools which they carry will cut a continuous channel in the face of the rock. 90 Each frame carries a motor-cylinder 58, whose position is connected with a cross-head 59 carrying the channeling tool 60. These cylinders are advanced or retracted by hydraulic feeding cylinders 61, which I employ for the first time for the purpose of feeding 95 the working cylinders of the tools, and as they render unnecessary the employment of feed nuts, they reduce greatly the wear of the machine and enhance its efficiency. The powerful action of the feed-cylinders enables me to draw back the tool quickly 100 if it happens to be lodged at the base of the cut, and I thus increase greatly the speed of channeling. Where it is desired to employ two channel-cutters at each side of the machine, the head 52 may be constructed to support two feed-cylinders and two cutting-cylinders placed directly above the set shown in the drawings. Such duplication is only necessary where the rock is of a hard nature. The cylinders 58 form the vertical channel-cuts of the tunnel. The curved channel-cut at the roof of the tunnel is 110 formed by another sliding head 62 which is hung from the top of the frame 5 by guides 63, along which it may be traversed by a pinion 64 meshing with a stationary rack 65 and driven by motors 66 through gearing 67. The head 62 can thus be moved around 115 the arch of the frame 5 from end to end thereof, and it carries channeling percussion-cylinders 66 and feed-cylinders 67 at its end, which are constructed and arranged as described with reference to the cylinders 58 and 61. These cylinders may be duplicated on the head 62, if desired. The head is kept in constant motion along its slide by the operation of the motor 66.

For the purpose of preventing lost motion or pounding of the feed-cylinders 67, I prefer to operate them 125 by keeping both ends in communication with the source of pressure, and to move them forward or back by exhausting the water from the end towards which motion is desired. It is clear that by proceeding in this way the water on both sides of the piston 130

will prevent any lost motion, and the feed can be controlled with great exactness.

Those skilled in the art, after becoming familiar with the construction above particularly described, 5 will be able to modify it in many ways without departure from the principles of my invention, as stated in the claims, since

What I claim is:—

1. Tunneling apparatus comprising a hollow shell carrying drilling machinery and made hollow for the passage 10 of cars; substantially as described.
2. In tunneling apparatus, a hollow shell closed at its top and sides and open at its ends and bottom to permit cars to pass therethrough, and drill mechanism carried by 15 said shell; substantially as described.
3. In tunneling apparatus, a hollow shell closed at its top and sides and open at its ends to permit cars to pass therethrough, and a drill mechanism movably mounted within the shell; substantially as described.
4. In tunneling apparatus, a hollow shell closed at the 20 top and sides, and open at the ends to permit cars to pass therethrough, drill mechanism movably mounted within the shell, and other drill mechanism mounted on the roof or top of the shell; substantially as described.
5. In a tunneling apparatus, a hollow shell closed at the 25 top and sides to protect workmen therein, and to form a platform for workmen on the top thereof, said shell being open at its ends to permit cars to pass therethrough, tracks upon which the shell is mounted, a motor on the shell for actuating the same, and drill mechanism carried by the shell; substantially as described.
6. In tunneling apparatus, a hollow shell, a vertically 30 movable drill carrying frame mounted therein, and having a forwardly projecting portion connected thereto for independent vertical movement whereby it may be given different angles of inclination, drills mounted thereon, and means for locking said portion in its different positions; substantially as described.
7. Tunneling apparatus comprising a frame carrying 35 channel-cutters, and drills exterior to the channel-cutters; substantially as described.
8. In tunneling apparatus, a hollow shell, a vertically 40 movable drill carrying frame mounted therein, and having a forwardly projecting portion pivoted thereto for independent vertical movement, and a rotary drill-carrying head carried by the pivoted portion; substantially as described.
9. In tunneling apparatus, a hollow shell, a vertically 45 movable drill-carrying frame mounted therein, and having a forwardly-projecting portion pivoted thereto for inde- 50 pendent vertical movement, a rotary head carried by said portion, a laterally sliding frame or carrier on the head, and a drill cylinder mounted on said frame or carrier; substantially as described.
10. In tunneling apparatus, a hollow shell, a vertically- 55 movable drill-carrying frame mounted therein, and having a forwardly-projecting portion pivoted thereto for independent vertical movement, a rotary head carried by said portion, a laterally sliding frame or carrier on the head, and a drill cylinder mounted on said frame or carrier by a vertical trunnion on which it can be swung laterally; substantially as described.
11. In tunneling apparatus, a hollow movable shell, vertically and angularly adjustable drill mechanism mounted within the shell and vertically-movable channel cutters 60 65 also mounted within the shell; substantially as described.
12. In tunneling apparatus, a hollow shell having channel cutters and carriages therefor, movable vertically within the shell, a curved track within the upper portion of the shell, a carriage movable on said track and a channel 70 cutter on said carriage; substantially as described.
13. In tunneling apparatus, a vertically-movable frame, means for raising and lowering the same, a motor cylinder mounted on the frame and having its piston connected with a channeling tool, and a feeding cylinder for advancing and retracting the motor cylinder; substantially 75 as described.
14. In tunneling apparatus, a hollow arched shell closed at its top and open at its ends, carriages mounted exteriorly on the top of the shell, and drill mechanism on the 80 carriages; substantially as described.
15. In tunneling apparatus, a hollow shell having a closed top, a carriage movably mounted upon said top, drills mounted on said carriage, and motor cylinders for actuating the drills; substantially as described. 85
16. In tunneling apparatus, a hollow arched shell closed at the top and having curved tracks at the upper interior portion thereof, a head movable on said tracks, channel cutting mechanism carried by said head, and a motor for actuating the head; substantially as described. 90
17. In tunneling apparatus, a hollow curved shell having the interior of its roof provided with tracks, a sliding head hung from the top of the shell and arranged to traverse said tracks, a motor for actuating the head and channel cutters carried by the head; substantially as described. 95

In testimony whereof, I have hereunto set my hand.

DAVID MAXWELL.
